United States Patent Office.

LEVI GRISWOLD, OF PORTLAND, AND GEORGE CAUL, OF YORK,
WISCONSIN.

Letters Patent No. 94,104, dated August 24, 1869.

IMPROVEMENT IN STEAM-ENGINE.

The Schedule referred to in these Letters Patent and making part of the same.

To all whom it may concern:

Be it known that we, LEVI GRISWOLD, of Portland, in the county of Dodge, and GEORGE CAUL, of York, in the county of Dane, and State of Wisconsin, have invented new and useful Improvements in Steam-Engines; and we do hereby declare that the following is a full, clear, and exact description of the same, reference being had to the annexed drawings, making part of this specification, in which—

Figure 1 is a plan or top view of our improved engine.

Figure 2 is a sectional elevation on line $x-x$ of fig. 1, showing the piston-valves in elevation.

Figure 3 is an elevation of the rear side of the steam-chest, showing the pipe for conducting the exhaust steam from the cylinder of the engine.

Figure 4 is an end view of the steam-chest and valve-cylinders.

Corresponding letters in the several figures refer to corresponding parts.

This invention relates to an improvement in reciprocating steam-engines, its object being to aid the cranks of such engines in passing the "dead-centres," or rather to aid in removing such cranks when the engine stops with its crank upon such centres, or in positions where the steam which is admitted to the cylinder will not start such engine; and to this end,

It consists in arranging the induction and eduction or cut-off valves of a steam-engine in such a manner, by means of a connection with the main shaft of an engine, that they may be used as a motive-power for starting the engine, when it stops with its crank upon either of such "dead-centres," as will be more fully described hereinafter.

A, in the drawings, represents the steam-induction pipe, to be attached to the steam-chest, as shown in the drawings, or it may be upon the side thereof.

B represents the upper compartment of the steam-chest, it being the one into which steam is admitted from the generator. From each end, or from near each end of this chest, there are ports or passages which lead into the valve-cylinder C, which, in this case, is immediately below the steam-chest, but which may, if preferred, be upon its side.

C represents the upper valve-cylinder or chest.

D represents a rod, which passes through a stuffing-box, to be formed upon the outer end of the chest, and is to be of sufficient length to reach to the opposite end thereof. Upon its inner end it is to be supplied with a piston of sufficient length to cover the aperture which leads from the steam-chest B, and form a steam-tight joint on each side thereof. At such a distance from this piston as will leave the aperture in the communicating-pipe f open when the first-mentioned piston is over its aperture, there is to

be secured another piston or valve of similar construction to the one above referred to. The office of these pistons or valves is to direct the steam from this compartment of the chest to the opposite ends of main or cut-off valves, and also to the space between such valves, for a purpose soon to be explained.

E represents another cylinder or valve-chest, which is arranged between the one, C, and that in which the main or cut-off valves are placed. This chest is supplied with a rod, having a handle upon its outer end for moving the same, and with pistons or valves within the chest, for giving direction to the steam, as in the case above alluded to. The office of the last-named pistons or valves is to direct the steam upon either outer end of the main or cut-off valves, when the engine stops with the crank upon either of its dead-centres, in order that such valves may be converted into an engine, for the time being, having sufficient force to start the crank of the main engine, and continue it in motion until it has passed far enough to admit sufficient steam behind the piston of the main engine to carry it forward, when, by means of the handle upon the valve-rod, the valves of which are to be moved by the hand of the operator, they are to be returned to such a position that they will admit steam to the outer ends of the main or cut-off valves.

F represents another rod, which passes through a stuffing-box in the end of the chest opposite to those above described, and which has upon it the main or cut-off valves or pistons, as shown in fig. 2 of the drawings.

To the outer end of this rod there is to be secured a cross-head, H, which is to run upon suitable ways, and have attached to it a connecting-rod, I, for the purpose of transferring the power or pressure upon the pistons or valves in cylinder F, to the crank k , as above described, and so that the crank of the main cylinder may be carried past or off from the dead-centres. This connection with the crank of the engine also serves as a means of working the valves in cylinder F, in such a manner that they may perform the functions of induction and eduction-valves, and, at the same time, cut off the steam at any desired point, which arrangement may be effected by making the valves on rod E of the proper length, and placing the crank k upon the shaft in its proper relation to the crank k' of the working-cylinder.

G represents the exhaust-pipe, which is to be secured to the side of compartment C of the steam or valve-chest, as shown in fig. 4 of the drawings.

f represents a steam-passage, which conducts the exhaust steam from cylinder F to the compartment or cylinder C, from which it escapes through pipe G.

This pipe or passage may also be used to conduct

steam from the chest or compartment C direct to the cylinder F, and between the pistons in such cylinder, from which it will pass through apertures *a* to the working-cylinder.

This result may be accomplished by pushing rod D in to its full extent, so that the outer piston shall be upon the inside of the end of pipe or passage *f*, when the steam will pass directly to the cylinder F, as above described, and between the pistons, at which time, if the pistons which are on rod E are brought to the positions indicated by red lines in fig. 2, the exhaust will pass up through cylinder E and into C, and out at pipe G.

If it is desired to change the direction of the steam, and admit it to the working-cylinder from the outer ends of the valves in F, it may be done by pulling the rod D out to its full length, or so far as to cause the piston or valve upon its outer end, to cover the part in the outer end of the chest or cylinder C, and open the port in pipe *f*, and at the same time place the rod E in the position shown in red lines, when steam will flow into the outer ends of F, and from thence to the working-cylinder, from which it will be exhausted between the valves or pistons, or F, and up through pipe *f*, into cylinder C, and out of pipe G.

The parts of this engine not heretofore described may be of any approved or known kind, but as they do not form any part of our present invention, they need not be particularly described here.

The operation of our improved engine will be as follows:

The parts having been constructed and arranged substantially as shown and described, and when it is desirable to have the engine run regularly and admit steam to the working-cylinder from the outer ends of the main valves, the rod D is to be placed in such a

position that steam will pass down through the port in the inner end of the steam-chest B, from whence it will pass to cylinder F.

When the valves are in this position, and the engine stops with the crank of its working-cylinder on its dead-centre, it is only necessary to move rod E, and the pistons or valves thereon, into such a position as will admit steam upon the outside of the valve or piston that will move the crank in the right direction, when the pressure upon such pistons or valves will cause it to turn the crank until the dead-centre is passed, and the engine moves on as usual.

Having thus described our invention, What we claim, and desire to secure by Letters Patent, is—

1. The combination of the induction-valves of a steam-engine, with a crank placed upon the shaft thereof, when so constructed, and arranged that such valves may be used to carry the crank of the working or main cylinder, past or away from the dead-centres or points, substantially as shown and described.

2. The arrangement of the valves or pistons upon rod F, with reference to cranks *k* and *k'*, upon the main shaft of an engine, it being such that the pressure applied to the ends of such pistons may be used to carry the cranks of the main or working-cylinders past or away from the dead-centres, in its revolution, substantially as shown and described.

It testimony whereof, we have signed our names to this specification, in the presence of two subscribing witnesses.

LEVI GRISWOLD.
GEORGE CAUL.
